Carl Cook Veneman, Beverly Hills, Calif., assignor of one-half to Leon M. Glaser, Beverly Hills, Calif.

Application April 6, 1940, Serial No. 91,518

Term of patent 7 years

To all whom it may concern:

Be it known that I, Carl Cook Veneman, a citizen of the United States, residing at Beverly Hills, in the county of Los Angeles and State of California, have invented a new, original, and ornamental Design for a Postal Scale, of which the following is a specification, reference being had to the accompanying drawing, forming part thereof.

I claim:

The ornamental design for a postal scale, as shown.

CARL COOK VENEMAN.
